HEATED GRID GAS ANCHOR

Robert L. Koch, Dallas, Tex., assignor, by mesne assignments, to Socony-Vacuum Oil Company, Incorporated, New York, N. Y., a corporation of New York

Application July 6, 1950, Serial No. 172,361

6 Claims. (Cl. 183—33)

1

This invention relates to gas anchors and relates more particularly to a heated grid gas anchor.

In the production of petroleum oil from subterranean reservoirs, the oil may be recovered originally as a result of the natural formation pressure forcing the oil from the reservoir to the surface of the ground. As production continues, however, the natural formation pressure decreases until ultimately it becomes insufficient to force the oil to the surface of the ground. At this point, production is customarily continued by employing pumps to bring the oil to the surface of the ground. Pumping is an effective means for recovering oil from a subterranean reservoir, but the use of pumps is attended with certain difficulties, particularly those arising from the presence of free or dissolved gases produced concomitantly with the oil. The free gases can enter the pump to cause vapor locking of the pump or to reduce its volumetric efficiency, and the dissolved gases, because of the decrease of the pressure on the oil as it enters the pump, tend to escape from solution in the oil resulting in the formation of a foam or a free gas phase to cause vapor locking of the pump or to reduce its volumetric efficiency. In order to separate the free gases concomitantly produced with the oil, a gas anchor is customarily employed in conjunction with the pump. However, the use of a gas anchor of the type usually employed does not ordinarily solve the problems arising from foaming or the formation of a free gas phase as a result of the escape of dissolved gases from the oil upon entrance of the oil into the pump.

It is an object of this invention to provide a gas anchor. It is another object of this invention to prevent foaming of oil upon entry into an oil well pump. It is another object of this invention to minimize formation of a free gas phase by escape of dissolved gas from petroleum oil upon entry of the oil into an oil well pump. It is another object of this invention to reduce the viscosity of oil entering an oil well pump. It is another object of this invention to facilitate separation of gas from oil within an oil well bore.

With the above and other objects in view, as will appear hereinafter, reference is directed to the accompanying drawings in which:

Figure 1 is an elevation in section of a gas anchor constructed in accordance with one embodiment of the invention, the view showing the well casing and pump;

Figure 2 is a plan view of Figure 1;

Figure 3 is a side view of a heating grid within the gas anchor;

2

Figure 4 is an isometric view, partly cut away, of the inner barrel of the gas anchor; and

Figure 5 is an isometric view, partly in section, of the outer barrel of the gas anchor.

Referring now to the figures, the gas anchor comprises an inner barrel 9, an outer barrel 10, an outer barrel cover 11, wall sections 12, 13, 14, 15, 20, and 21 forming segmental chambers 22, 23, 24, 25, 30, and 31 within the annulus between the barrels, heating grids 32, 33, and 34 within chambers 23, 25, and 31, respectively, and a floor closure or partition 35 forming an oil collecting chamber 36 within the inner barrel 9. The gas anchor, as shown, is positioned at the end of the well tubing 37 containing oil well pump 38. While one particular type of pump is illustrated, any suitable type of oil well pump may be employed.

Inner barrel 9 comprises an elongated cylinder having a diameter sufficient to accommodate the oil well tubing 37 and attached thereto are the wall sections 12, 13, 14, 15, 20, and 21. The wall sections may be integrally connected to the cylinder, as shown, by casting the cylinder and the wall sections in one piece. However, the wall sections may be attached to the cylinder by any suitable means such as welds, bolts, rivets, etc. The wall sections extend to the bottom edge of the cylinder but only wall sections 12, 14, and 20 extend to the upper edge of the cylinder, wall sections 13, 15, and 21 extending to a point sufficiently below the upper edge of the cylinder to provide a weir, as hereinafter more fully explained. The inner barrel is provided with a port between each of segmental chambers 22, 24, and 30, ports 39 and 40 being shown, and chamber 36 formed by the floor partition 35, the barrel, and the bottom sections of the well tubing 37.

To the surface of the upper edge of the inner barrel are attached, by suitable means, two arcuate plates 44 and 45 provided with bolt holes 46 and 47, respectively, to accommodate bolts 50 and 51, respectively, for attaching the anchor to the well tubing 37. Wall sections 12, 14, and 20

are provided at their upper and lower edges with dogs 52 having bolt holes 53 to cooperate with bolt holes 54 in the outer barrel 10 for attaching the outer barrel to the dogs by means of bolts 55. The dogs may be attached to the wall sections

50 by any suitable means such as welds, bolts, rivets, or may be integrally connected with the wall sections as by casting the wall sections and the dogs in one piece. Attached to the outer face of the inner barrel 9 are a plurality of hangers 60. The hangers 60 are preferably attached to the barrel 9 by welds or other means that will not involve

protrusion of a member beyond the inner face of the barrel interfering with the reciprocating motion of the pump 38. Floor partition 35 is positioned by attaching to the face of the bottom edge of barrel 9 or to the wall sections 12, 13, 14, 15, 20, and 21 or to both, or to one or more but not all of the wall sections, as desired. However, regardless of the method of attachment, the abutting surfaces of the floor partition, the face of the barrel, and the wall sections should be sufficiently close or be sealed in order to prevent leakage therebetween of no more than inconsequential amounts of oil and gas. The same is true with respect to the abutting edges of the wall sections and the outer surface of the inner barrel.

Heating grids 32, 33, and 34 are positioned within the segmental chambers 23, 25, and 31 formed by the inner barrel 9, the outer barrel 10, the wall sections 12, 13, 14, 15, 20 and 21, and the floor partition 35, and are supported therein by means of the hangers 60. The heating grids 32, 33, and 34 may be of any desired type, for example, the grids may be electrically operated heating elements, steam heated tubes, hot water heated tubes, oil heated tubes, etc. In the embodiment illustrated, tubes heated by steam, water, oil, etc., are employed.

The heating grids are shaped in such manner that linear flow of oil without interference by the heating grids is eliminated or at least minimized whereby channeling of oil is eliminated or minimized and effective heating is obtained. In the embodiment illustrated, the heating grid, referring to Figures 1, 2, and 3, extends from one wall partition to the other wall partition following the arcuate shape of the inner and outer barrels and each loop of the grid is displaced a slight distance radially from the succeeding loop. By this arrangement, an unobstructed passage for flow of oil through the segmental chambers is not present, the oil follows a devious passage, agitation during flow occurs, and effective heating of the oil is obtained.

Heating medium for the grids is supplied thereto from a suitable source through line 61 leading to grid 34. The heating medium leaves grid 34 through line 62 leading through suitable openings in floor partition 35, such as opening 63, and passes through grid 32. After passage through grid 32, the heating medium passes through line 64 to grid 33 and then passes through line 65 to be conducted away from the anchor for reheating.

The outer barrel 10 comprises an elongated cylinder adapted to fit over the inner barrel and to contact at its inner face the wall sections 12, 13, 14, 15, 20, and 21. The abutting surfaces of the wall sections and the inner face of the barrel and the face of the periphery of the floor partition 35 should be sufficiently close or be sealed, similarly to the abutting surfaces of the floor partition, the outer face of the inner barrel, and the wall sections, to prevent leakage therebetween of no more than inconsequential amounts of oil. The upper edge of the barrel 10 contains threads 66.

The barrel 10 is provided at three sections 70, 71, and 72, these sections corresponding to the portions of the barrel 10 adjacent to the segmental chambers 23, 25, and 31, with a plurality of oil entry ports 73, which may be in the form of slots. The sections 70, 71, and 72 extend along the barrel from a point above the point where the barrel contacts the floor partition 35 to a point 75

which preferably is not above one-half of the length of the segmental chambers. However, the length of the sections may be as small or as large as desired depending upon the rate of oil flow, the temperature of the heated grids, and the temperature to which the oil is to be heated. The width of the sections 70, 71, and 72 should be no greater than the width of the segmental chambers 23, 25, and 31. Closing the bottom of the outer barrel 10 is a cover 74.

The barrel cover 71 fits on outer barrel 10 by cooperation of threads 67 and threads 66 and the well tubing passes through the throat 75 of the cover. The cover is provided with a gas outlet 16 comprising a nipple 77 containing a ball valve 18 normally positioned on valve seat 79 by valve spring 80. The cover is also provided with ports 81 and 82 to accommodate lines 61 and 65. To prevent leakage of oil from the well past the cover to within the anchor, the cover is provided with gasket rings 83, 84, 85, and 86.

With the anchor assembled and positioned at the bottom of the well tubing 31, heating fluid flowing through the grids, and with the pump 38 operating within the tubing, petroleum oil from the well enters the lower portion of the segmental chambers 23, 25, and 31 through the perforated sections 70, 71, and 72 and flows upwardly through the chambers over the heated grids. As a result of passage over the heated grids, the oil is heated whereby the dissolved gases are removed from the oil. Further, as a result of passage of the oil over the heated grids, producing agitation as well as heating of the oil, foam produced as a result of the release of dissolved gas is broken. The oil flows upwardly through the segmental chambers until it reaches the level of the wall sections 13, 15, and 21. These wall sections, being at a lower level than the wall sections 12, 14, and 20, provide weirs and the oil flows over the weirs into the segmental chambers 22, 24, and 30 and thence downwardly therethrough. During passage downwardly through the chambers 22, 24, and 30, time is provided for further release of dissolved gas from the oil and for breaking of foam, and, because of the reduced viscosity of the heated oil, the slip velocity of released gas is increased minimizing entrainment of released gas. The heated oil enters the chamber 36 through the ports, such as ports 39 and 40, in the segmental chambers 22, 24, and 30. The released gas flowing upwardly through the chambers leaves the anchor through the outlet 16 and flows upwardly through the well between the casing (not shown) and the tubing, flow of oil through the gas outlet into the anchor being prevented by the ball valve 18.

The pump 38 operates by reciprocating motion within the tubing 31 and is activated by a sucker rod (not shown) adapted to be attached to the threaded end 90 of the pump. Upon upward motion of the pump, oil flows from the chamber 36 into the tubing through port 91 displacing ball valve 92. Upon downward motion of the pump, the oil which has entered the tubing is forced into chamber 93 through port 94 provided with ball valve 95, ball valve 92 closing port 91. With the next upward movement of the pump, ball valve 95 closes port 94 and the oil in the chamber 93 is carried with the pump to be displaced through port 96 into the tubing upon the next downward movement of the pump.

Having thus described my invention, it will be understood that such description has been given by way of illustration and example and not by

way of limitation, reference for the latter purpose being had to the appended claims.

I claim:

1. A gas anchor comprising in combination an inner chamber adapted for communication with the tubing of a pumping oil well, a plurality of chambers surrounding said inner chamber, a heating grid in at least one but not all of said chambers surrounding said inner chamber, an oil entry port leading from without to within each of said chambers containing a heating grid, an oil entry port leading to said inner chamber from each of the remaining chambers surrounding said inner chamber, means for passage of oil from each of said chambers containing a heating grid to a chamber containing an oil entry port leading to said inner chamber, and means for escape of gas from said chambers surrounding said inner chamber.

2. A gas anchor comprising in combination an inner chamber adapted for communication with the tubing of a pumping oil well, an even number of chambers surrounding said inner chamber, a heating grid in each alternate chamber surrounding said inner chamber, an oil entry port leading from without to each of said chambers containing a heating grid, an oil entry port leading to said inner chamber from each remaining chamber surrounding said inner chamber, means for passage of oil from each chamber containing a heating grid to one adjacent chamber containing an oil entry port leading to said inner chamber, and means for escape of gas from said chambers surrounding said inner chamber.

3. A gas anchor comprising in combination an inner barrel, an outer barrel surrounding said inner barrel, closure means for the bottom of said inner barrel and of the annulus formed by said inner barrel and said outer barrel, wall sections between said inner barrel and said outer barrel forming a plurality of chambers within the annulus formed by said inner barrel and said outer barrel, a heating grid within at least one but not all of said chambers, means for passage of oil from outside said outer barrel to said chamber containing said heating grid, means for passage of oil from said chamber containing said heating grid to a chamber not containing a heating grid, means for passage of oil from said last mentioned chamber to within said inner barrel, and means associated with said outer barrel for escape of gas from within said outer barrel.

4. A gas anchor comprising in combination an inner barrel, an outer barrel surrounding said inner barrel, closure means for the bottom of said inner barrel and of the annulus formed by said inner barrel and said outer barrel, a plurality of wall sections between said inner barrel and said outer barrel forming a plurality of chambers within the annulus formed by said inner barrel and said outer barrel, a heating grid within each

of a plurality but not all of said chambers, means for passage of oil from outside said outer barrel to said chambers containing said heating grids, means for passage of oil from each of said chambers containing a heating grid to a chamber not containing a heating grid, means for passage of oil from said last mentioned chamber to within said inner barrel, and means associated with said outer barrel for escape of gas from within said outer barrel.

5. A gas anchor comprising in combination an inner barrel, an outer barrel surrounding said inner barrel, a floor partition closing the bottom end of said inner barrel and the bottom end of the annulus formed by said inner barrel and said outer barrel, a plurality of wall sections between said inner barrel and said outer barrel forming a plurality of chambers extending lengthwise within the annulus formed by said inner barrel and said outer barrel, a heating grid within each of a plurality but not all of said chambers, oil entry ports in said outer barrel leading to said chambers containing said heating grids, means for passage of oil from each of said chambers containing a heating grid to a chamber not containing a heating grid, oil entry ports in said inner barrel leading to each of said chambers not containing a heating grid, and means associated with said outer barrel for escape of gas from within said outer barrel.

6. A gas anchor comprising in combination an inner barrel, an outer barrel surrounding said inner barrel, a floor partition closing the bottom end of said inner barrel and the bottom end of the annulus formed by said inner barrel and said outer barrel, an even number of wall sections between said inner barrel and said outer barrel forming a plurality of chambers extending lengthwise within the annulus formed by said inner barrel and said outer barrel, a heating grid within each alternate chamber, an oil entry port through said outer barrel leading to each of said chambers containing a heating grid, an oil entry port through said inner barrel leading to each remaining chamber, means for passage of oil from each chamber containing a heating grid to one adjacent chamber containing an oil entry port through said inner barrel, and means associated with said outer barrel for escape of gas from within said outer barrel.
